COMBINATION SPRAY UNIT AND SUCTION CUP
FOR AUTOMOBILE WASHING

Robert E. Block, 15192 Warwick Circle,
Westminster, Calif.

Filed June 7, 1965, Ser. No. 85,672

Term of patent 14 years

(Cl. D49—1)

FIG. 1 is a top front left isometric view of a combination spray unit and suction cup for automobile washing showing my new design thereof;

FIG. 2 is a right side elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a combination spray unit and suction cup for automobile washing, substantially as shown.
